UNITED STATES PATENT OFFICE.

FOIRE RICCIARDELLI, OF JERSEY CITY, NEW JERSEY, ASSIGNOR OF ONE-HALF TO
BENEDETTO FREDA, OF JERSEY CITY, NEW JERSEY.

CHAIR.

1,248,915.

Specification of Letters Patent. Patented Dec. 4, 1917.

Application filed December 17, 1914. Serial No. 877,765.

To all whom it may concern:

Be it known that I, FIORE RICCIARDELLI, a citizen of the United States, residing at Jersey City, in the county of Hudson and 5 State of New Jersey, have invented a certain new and useful Improvement in Chairs, of which the following is a specification.

The object of my invention is to provide a chair which will always present a cool, sanitary seat to one desiring to occupy the chair. After a chair has been occupied any considerable time the body heats the seat rendering the occupancy of the chair immediately after its vacation uncomfortable, 5 and sometimes, perhaps, causing or aggravating disorders. I also provide a chair, the back of which may always be kept cool and comfortable.

While I have shown and described a barber's chair embodying my invention, I desire it distinctly understood that I do not desire myself limited to such chairs.

I will first describe my improvement in detail and then point out the novel features 5 in the claim.

In the accompanying drawings Figure 1 is a front elevation of a chair embodying my improvement; Fig. 2 is a vertical section of the chair illustrated in Fig. 1; Fig. 3 is an elevation of the back of the chair illustrated in Fig. 1; Fig. 4 is a side elevation of the chair illustrated in Fig. 1; Fig. 5 is a detail view of parts of a chair embodying my improvement; Fig. 6 is a view taken 5 through the plane of the dotted line 6—6, Fig. 3; and Fig. 7 is a view showing a modified form of parts of a chair embodying my improvement.

Similar letters of reference designate corresponding parts in all the figures.

A designates the frame of a chair back. To this frame A a head rest B is shown as attached.

C designates the arms of a chair, which 5 arms are supported at their rear ends by knuckles D' hinged at d to web pieces A' of the frame A. The pieces A' are shown as also hinged at d' to rear standards D² fastened to the seat frame D⁴, and E designate rods 5 shown as pivoted to the front standards D³ at e. The rods E are shown as hinged to the front knuckles D at e'. A foot rest of any desired construction may be attached to the lower ends of the rods E.

It has been found desirable to so construct

barber chairs that the backs thereof may be adjusted at any desired angle, that the seats thereof may be raised and lowered, and that the body of the chair may be revolved.

The movement of the chair back backward 60 draws backward with it the arms, and this carries backward the upper ends of the rods E, thereby causing an upward movement of the lower ends of the rods E and of the foot rest attached thereto. As, however, the adjustment of the chair back and of the parts connected therewith and means for locking the chair back and parts connected therewith in any desired position and for releasing the chair back and parts connected therewith from any position in which they may be locked, form no part of my present invention I have not thought it necessary to illustrate or describe such means.

Any suitable mechanism may, of course, 75 be employed to raise and lower the chair seat, but as such mechanism forms no part of my present invention I have omitted to illustrate and describe such mechanism. For the same reason I have omitted to illustrate or describe means for permitting the body of the chair to be revolved on the base G.

H designates a chair back shown as pivoted in the frame A at h, and h' designates 85 a handle by which the chair back H may be turned. The chair back H is shown as provided with recesses h² h³ in its upper and lower ends respectively.

I designates a bolt shown as provided 90 with a handle i. The upper end of this bolt is shown as provided with a head i', and a coiled spring i² is shown as seated in the seat frame D⁴ and has bearing against the head i'. The head i' may have attached 95 thereto or made integral therewith a pin i³ so shaped as to fit into the recesses h² h³. This pin, which is really the tip of the bolt, is preferably inclined to the rear as best seen in Fig. 4 so that it will engage one of 100 the recesses in the chair back whether the latter stands at its usual position as seen in that view or is inclined farther to the rear as is sometimes desired. In that case the back frame and back swing around the 105 center d' and the lower edge of the back of course descends toward the seat frame, but the spring i² under the head of the bolt I permits the descent of the tip i³ so that the latter does not need to be disengaged from 110

the lowermost socket unless the back is adjusted quite far to the rear. Moreover, the inclination of the tip i^3 to the rear is such that it stands practically tangential to an arc drawn around the center d' and through the lowermost recess which is h^3 in Fig. 6, and this fact—in addition to the looseness of the tip within the recess and the pivotal mounting of the back in the back frame—
10 prevents the parts from binding while the back is swung to the rear some little distance. Of course if it is to be swung to the rear into nearly a horizontal position, as often occurs when the barber is shaving his
15 customer, it will be necessary to disengage the bolt from the socket before swinging the back to such an extreme. This can be accomplished by depressing the handle i so as to draw the head of the bolt and its tip
20 well down into the socket in the seat frame (best seen in Fig. 6), after which the back frame may be swung to the rear as far as possible and, as the construction permits, and the lower edge of the back will then
25 rest upon the rear cross bar of the seat frame as will be clear.

J designates a chair seat shown as pivoted in the seat frame D^4 at j' , and j designates a handle by which the chair seat J may be turned. The chair seat J is shown as provided with recesses j^2 j^3 in its rear and front edges respectively.

In Fig. 2 K designates a bell crank lever fulcrumed at k and provided with a handle k' . A bolt k^2 , may be made integral with or secured to this bell crank lever K and a spring k^3 is shown as bearing against the bell crank lever K to press the bolt forward through an opening in the seat frame into
35 the recesses j^2 j^3 . A latch L is shown pivoted at l , and a spring l' is shown as pulling the lower end of the latch forward to throw its beveled tip normally into the recess which is at the front at that time. It
40 will be observed from Fig. 2 that the bevel is on the under side of the tip, and therefore the straight face of this tip positively supports the front edge of the seat J and the weight of the person thereon, even
45 though the bolt at the rear should be retracted. The use of this tip makes it necessary in reversing the seat to raise its front edge and turn it over to the rear.

The seat frame D^4 is shown as affixed to
55 a support as M . This support M is shown as so shaped as to permit the chair seat J being turned therein.

In Fig. 7 I have shown another form of bolt. This is a plunger N provided at one
60 end with a knob or handle n and as encircled by a spring n' , one end of which is shown as resting against the frame D^4 and

the other end of which is shown as resting against a collar n^2 made integral with or secured to the plunger N . The end n^3 of
65 the plunger N will, of course, be so shaped as to fit into the recesses j^2 j^3 .

To reverse the chair back H the bolt I may be pulled down to draw the pin i^3 out from the recess h^3 , and the chair back H 70 may then be turned either by pushing the chair back H around or by turning the handle h' . When the chair back H has been turned around sufficiently the recess h^2 will present itself to the pin i^3 and the 75 spring i^2 will force the pin i^3 into the recess h^2 , thereby locking the chair back H in position.

To reverse the chair seat J the handle k' may be pulled down in the direction of the 80 arrow, Fig. 2, and the bolt k^2 thereby withdrawn from the recess j^2 . The chair seat J may then be turned either by pushing it around or by turning the handle j . By pressure on the rear of the chair seat J or by 85 turning the handle j in the proper direction the front of the chair seat J will rise and the latch L will be thrown out of engagement with the recess j^3 . When the chair seat J has been turned around sufficiently 90 the latch L will engage the recess j^2 and the bolt k^2 will engage the recess j^3 and the chair seat J will thereby be locked in position.

The plunger bolt N (Fig. 7) may, of 95 course, be used instead of the bell crank lever K and bolt k^2 (Fig. 2).

What I claim as my invention and desire to secure by Letters Patent is:

The combination with a frame for the 100 seat of a chair of a seat portion pivoted therein, said frame having an inwardly extending flange adjacent to one side of the seat and having an outwardly extending flange along a side opposite the flange first 105 mentioned, said outward flange extending rearwardly, and then downwardly to form a space between the flange and the frame, a pawl extending through an opening in the frame engaging one edge of the seat, an 110 angular member pivoted to the frame and having one end connected with the pawl, the opposite end of the angular member extending outwardly below the free edge of the flange, a spring between the edge of the 115 flange and the angular member, and a second pawl pivoted below the flange on the opposite side of the frame for engaging the seat portion at that point.

FIORE RICCIARDELLI.
